MAGNETIC ELECTRON LENS

Johan Anton Verhoeft and Wilhelm Godfried Ames, Eindhoven, Netherlands, assignors, by mesne assignments, to North American Philips Company, Inc., New York, N. Y., a corporation of Delaware

Application November 28, 1952, Serial No. 322,962

Claims priority, application Netherlands January 4, 1952

8 Claims. (Cl. 313—84)

This invention relates to magnetic electron lenses with adjustable focal length such as are used, for example, for focusing the electron beam in cathode-ray tubes, for example of television receivers.

In a known device of this type, use is made of a permanent magnet having rotational symmetry and being magnetized in an axial direction, the focal length of the lens being variable by means of a movable cylindrical ferro-magnetic shunt embracing the permanent magnet.

Such electron lenses suffer from the disadvantage that the stray or leakage field produced outside the permanent magnet is unduly large. Notably in cathode-ray tubes for television receivers, said leakage field has been found to extend to the deflection coil or to the ion trap, which involves undue distortion of the deflection of the beam and causes the ion trap to cease to function properly.

The present invention has for its object a magnetic electron lens of variable focal length with which said stray field is avoided in a simple manner. It is characterized by the use of two, co-axial, disc-shaped, permanent magnets which are movable with respect to each other and the fields of which substantially neutralize each other on the axis outside the magnets. According to a further aspect of the invention, said neutralization is achieved in a simple manner by opposite directions of magnetisation of both magnets.

In order that the invention may be readily carried into effect, it will now be described with reference to the accompanying drawing representing embodiments thereof and in which:

Fig. 1 illustrates the principle of a magnetic electron lens in which the permanent magnets are magnetized radially in.

Fig. 2 shows the principle of a magnetic electron lens in which the permanent magnets are magnetized axially;

Fig. 3 is a cross-sectional view of the neck area of a cathode-ray tube in a television receiver and containing a focusing, magnetic lens of the invention.

In the three figures, corresponding elements are provided with the same reference numerals.

The magnetic electron lens shown in Fig. 1 comprises two, annular, disc-shaped, co-axial, permanent magnets 1 and 2, whose directions of magnetisation NS extend radially i. e. for the magnet 1 from the inside to the outside, and for the magnet 2 from the outside to the inside. In this manner, a radially symmetric electron-focusing magnetic field is produced about the axis of symmetry 3 of the magnets 1 and 2, the value H_1 of said active magnetic field between the magnets being fairly high. However, the stray field H_2 outside the magnets is feeble, since the outside fields produced by each individual magnet 1 and 2 substantially neutralize each other in situ. In order that the field H_3 at the outer periphery of the magnets shall not extend too far, a ferromagnetic, for example soft iron, shielding box 4 may be provided. As will be noted, however, the space between the magnets 1 and 2 is free of other ferromagnetic members.

The focal length of the electron lens is adjustable by

2

making, for example, the magnet 2 stationary and by shifting the other magnet 1 in an axial direction by means of a driving mechanism 5, the co-axial position of the magnets 1 and 2 being maintained by means of a guide (not shown). In this instance compression springs are unnecessary, since the magnets 1 and 2 attract each other continuously.

Fig. 2 shows a similar electron lens, but in this instance the annular permanent magnets 1 and 2 are magnetized axially with opposite directions of magnetisation NS. Such a lens has the advantage over that shown in Fig. 1 that the active field H_1 along the axis at the magnet 1 is as large and oppositely directed compared with that at the magnet 2 resulting in avoidance of image rotation. Further, since the magnets repel one another, the focus-changing mechanism 5 is now required to engage that side of the magnet 1 which faces away from the stationary magnet 2, thus simplifying the construction.

In order that centering of the image produced may be controlled, a plate 6 movable in a radial direction may be provided in the proximity of the side of the magnet 1 facing the source of electrons, said plate causing dissymmetry of the magnet field with consequent image displacement.

Notably with the electron lens shown in Fig. 2, where the direction of magnetisation NS coincides with the direction of thickness of the magnets 1, 2 and, moreover these magnets are influenced by their respective demagnetizing fields, the permanent magnetic material preferably has a remanent induction B_r which, measured in gauss, is smaller than four times the coercive field strength B_{HC} measured in oersteds, since in spite of the demagnetizing fields the magnets retain their magnetic properties to a sufficient degree. Materials satisfying this condition and suitable for application in the invention are the permanent magnet materials which are fully described in United States Patent No. 2,762,777. These materials are characterized by a composition substantially consisting of non-cubic crystals consisting principally of a composite oxide of iron and of at least one of the metals barium, strontium and lead, and, alternatively, a small amount of calcium as a partial substituent for one of the latter metals.

Fig. 3 shows the lens of Fig. 2 mounted in position on the neck of a cathode-ray tube 10 adapted for use in a television receiver. Only the neck portion of the cathode-ray tube 10 is shown, the electron-receiving, phosphor screen (not shown) being located at the right. The tube contains the usual bent, electron gun 11 for producing an electron beam free of ions along the axis 3 of the tube and the lens. This end is attained in cooperation with an ion trap 12 mounted on the neck and producing within the tube a magnetic field. Closer to the phosphor screen are the usual deflection coils 13, which establish within the tube a magnetic field causing the beam to scan a raster on the phosphor screen. The focusing unit for the beam, which is magnetic in this case, is mounted between the ion trap and deflection coils. Due to the nearness of the latter, as explained above, the stray or leakage field of the focusing unit should be a minimum, especially along the axis 3, to avoid interference with the ion trap and deflection fields. This effect is obtained with the lens of the invention, as the opposed magnetization of the two magnets tends to neutralize the axial, external, stray fields. To vary the lens power or its focal length, the axial spacing between the magnets may be varied. As shown, this is obtained by making the magnet 2 stationary, and providing means 5 for axially displacing the magnet 1 relative thereto.

What we claim is:

1. In combination, means producing a charged particle

beam along a given path and means for focusing the beam, said focusing means comprising a pair of substantially co-annular, permanent magnets mounted substantially coaxially with and adjacent one another and surrounding the beam path and cooperating to produce an active magnetic field substantially at their axes and substantially in the area within the magnets, said magnets being magnetized in opposite directions whereby the stray magnetic fields produced by said pair of magnets at their axes on the side of each magnet remote from the other magnet are substantially neutralized, and means for varying the axial spacing between the magnets thereby to vary the strength of the active magnetic field and the focusing effect on the beam.

2. A variable magnetic electron lens adapted for focusing an electron beam passing therethrough, comprising two, flat, ring-shaped, permanent magnets mounted adjacent and coaxial with one another, said permanent magnets defining therebetween an area free of other ferromagnetic material and defining along the axes of and within the coaxial magnets an empty area to be traversed by the electron beam and within which an active magnetic field is established by said cooperating magnets to focus said beam, said magnets being magnetized in opposite directions whereby the stray magnetic fields produced on the axes but outside the magnets are reduced to a minimum, and means for varying the axial spacing of the magnets thereby to vary the strength of the active magnetic field and the focusing effect on an electron beam.

3. A variable magnetic electron lens as set forth in claim 2, wherein the permanent magnets are each constituted of a ferromagnetic material having a ratio of remanence in gauss to coercive field strength BH_c in oersteds of less than 4.

4. A variable magnetic electron lens as set forth in claim 3, wherein the ferromagnetic material consists principally of a composite oxide of iron and a metal selected from the group consisting of barium, strontium and lead.

5. A variable permanent magnet focusing device comprising a pair of coaxially-mounted, adjacent, disc-shaped, annular, permanent magnets, said magnets being magnetized in a direction parallel to their axes but in opposite directions, thereby producing poles of the same polarity

on facing surfaces of said magnets, and means for varying axially the spacing between the magnets thereby to vary the strength of a magnetic field produced by said device.

6. In combination, means producing a charged particle beam along a given path and means for focusing said beam, said focusing means comprising a pair of coaxially-mounted, adjacent, disc-shaped, permanent magnets, surrounding the beam path, said magnets being magnetized in a direction at right angles to their axes but in opposite directions, thereby producing poles of opposite polarity on the outer peripheral surfaces of said magnets, and means for varying axially the spacing between the magnets thereby to vary the strength of the magnetic field produced by said focusing means at the beam path and thus vary the focusing effect on the beam.

7. In combination, means producing an electron beam along a given path and means for focusing said beam, said focusing means comprising a pair of coaxially-mounted, adjacent, disc-shaped, permanent magnets surrounding the electron beam path, said permanent magnets being magnetized in opposite directions and establishing a strong, active, magnetic field at the beam path within the magnets but a weak stray field at the beam path outside of the magnets, thereby to limit the active magnetic field of the focusing means to their immediate vicinity, said focusing means including means for varying the spacing between the magnets by moving the magnets relative to one another thereby to vary the focusing of the electron beam.

8. A combination as set forth in claim 1, wherein means are provided for centering the charged particle beam, said centering means comprising a radially-movable plate-like member mounted adjacent the side of one of the magnets remote from the other magnet.
